UNITED STATES PATENT OFFICE.

WILLIAM M. WEBBER, OF GROVELAND, FLORIDA, ASSIGNOR, BY DIRECT AND MESNE ASSIGNMENTS, OF ONE-FOURTH TO HENRY W. SHEPPARD AND ONE-FOURTH TO ELIZABETH ELZENA SHEPPARD, BOTH OF GROVELAND, FLORIDA.

RUDDER MECHANISM FOR AIRSHIPS.

1,165,731.

Specification of Letters Patent. Patented Dec. 28, 1915.

Original application filed December 31, 1914, Serial No. 879,913. Divided and this application filed March 12, 1915. Serial No. 13,923.

To all whom it may concern:

Be it known that I, WILLIAM M. WEBBER, a citizen of the United States, residing at Groveland, in the county of Lake and State 5 of Florida, have invented certain new and useful Improvements in Rudder Mechanism for Airships, of which the following is a specification.

The present invention relates to a rudder 10 for airships, and has for its object to provide a device of this character which embodies novel features of construction whereby it has a universal movement and can be readily swung into any desired angular 15 position for directing the movements of the airship in the required manner.

Further objects of the invention are to provide an airship rudder which is comparatively simple and inexpensive in its 20 construction, which can be easily manipulated by the operator, which is dependable in its action, and which is not liable to be broken or get out of repair.

With these and other objects in view, the 25 invention consists in certain novel combinations and arrangements of the parts as will more fully appear as the description proceeds, the novel features thereof being pointed out in the appended claims.

30 For a full understanding of the invention, reference is to be had to the following description and accompanying drawings, in which:—

Figure 1 is a side elevation of a portion 35 of an airship provided with a rudder constructed in accordance with the invention, the rudder being shown in one position by full lines and in an adjusted position by dotted lines. Fig. 2 is an enlarged detail 40 perspective view of the rudder mechanism, showing the same as detached from the airship. Fig. 3 is a longitudinal sectional view through the rudder mechanism, portions being broken away.

45 Corresponding and like parts are referred to in the following description and indicated in all the views of the drawings by the same reference characters.

The subject-matter of this application 50 has been divided out from my copending application for improvements in airships, Serial No. 879,913, filed December 31, 1914.

Referring to the drawings which serve to

illustrate one possible embodiment of the invention, the numeral 1 designates an elongated gasbag, and 2 supporting planes which project laterally from opposite sides of the gas bag, both the gas bag and supporting planes being mounted upon and held in proper relative position by means of a frame 3. A suitable boat 4 is arranged under the gas bag 1 and supporting planes 2, and suspended from the frame 3 by means of suitable hangers and brace members 5. Any suitable lifting and driving means, such as that illustrated 65 in my copending application, Serial No. 879,913, may be mounted upon the boat.

The present invention resides more particularly in the construction and manner of mounting of the rudder mechanism which 70 is employed for directing the movements of the airship when in motion and causing the same to turn to the right or to the left, or up or down. The rudder member is shown as comprising four wings 13 which are arranged at right angles to each other and radiate from the axis of a rudder post or stem 14, such a construction enabling the 75 rudder to be effectively used for guiding the machine in any direction.

The rudder supporting frame is mounted upon the rear end of the boat 4 and includes a pair of spaced heads 15 connected at their lower edges by a suitable base 16. Should the supporting frame project rearwardly 85 from the boat, as in the present instance, the overhanging rear end thereof can be supported by a suitable brace 14a. The forward end of the rudder stem or post 14 projects loosely through an opening in one of 90 the heads 15, while the operating lever 19 projects loosely through a similar opening 20 in the opposite head 15. Both the rudder post 14 and operating lever 19 are mounted to have a universal swinging movement, and 95 when adjusted to direct the airship straight ahead are in alignment with each other.

Suitable thrust joints are provided for preventing the rudder post 14 and operating lever 19 from being pulled longitudinally 100 from the heads 15. As indicated upon the drawing, the rudder post 14 is provided with an annular enlargement or thrust collar 21 which engages the inner face of the head 15 and bears loosely against the same. A similar enlargement or thrust collar 22 is ap-

plied to the operating lever 19 so as to bear loosely against the inner face of the opposite head 15.

The inwardly projecting ends of the rudder post 14 and operating lever 19 are connected by a series of flexible cables 23, said cables passing around suitable guide members such as the pulleys 24 applied to the opposite heads 15. The portions of the cables 23 between corresponding guide pulleys 24 upon the opposite heads 15 are parallel to each other and to the normal position of the rudder post and operating lever, and the cables are adapted to move freely around the guide pulley so that any movement of the operating lever will be instantly transmitted to the rudder. As soon as the operating lever is swung into an angular position the rudder post is swung into a corresponding angular position, so that the aviator has the rudder under his complete control and can instantly swing the rudder into any desired angular position for guiding the machine up and down or laterally in either direction. The use of the flexible cable 23 enables the operating lever 19 to be located at a distance from the rudder and placed in a position adjacent to the seat of the aviator so as to be readily grasped and manipulated by him.

Having thus described the invention, what I claim as new and desire to secure by Letters Patent, is:—

1. A rudder for airships, including a frame formed with spaced and parallel heads, a rudder post passing loosely through one of the spaced heads, an operating lever passing in a similar manner through the opposite head so as to be disposed normally in alignment with the rudder post, thrust joints between the rudder post and operating lever and the respective heads, corresponding guide members upon the two parallel heads, cables passing around the corresponding guide members and having the extremities thereof connected to the inwardly projecting ends of the rudder post and operating lever, respectively, so that when the operating lever is moved an identical swinging movement is given to the rudder post, and a

rudder member mounted upon the rudder post.

2. A rudder for airships, including a frame formed with spaced and parallel heads having corresponding openings therein, a rudder post extending loosely through the opening of one of the heads, an operating lever extending loosely through the opening of the opposite head, thrust collars applied to the rudder post and operating lever respectively so as to engage and bear loosely against the inner faces of the respective heads, corresponding guide members upon the heads, cables passing around the corresponding guide members and having the extremities thereof connected to the inwardly projecting ends of the rudder post and operating lever, respectively, so that when the operating lever is moved an identical movement is imparted to the rudder post, and a rudder member upon the rudder post.

3. A rudder for airships, including a frame formed with spaced and parallel heads having corresponding openings therein, a rudder post extending loosely through the opening of one of the heads, a loose joint between the rudder post and the head so that the former is free to swing in all directions, an operating lever extending loosely through the opening in the opposite head, a loose joint between the operating lever and opposite head so that the lever is free to swing in all directions, two sets of correspondingly disposed guide members mounted upon the respective heads, cables passing around corresponding guide members of the two sets and having the extremities thereof connected to the ends of the rudder post and operating lever respectively so that when the operating lever is moved an identical movement is imparted to the rudder post, and a rudder member applied to the rudder post.

In testimony whereof I affix my signature in presence of two witnesses.

WILLIAM M. WEBBER.
